UNITED STATES PATENT OFFICE

EVELYN HURDEN AND ALFRED PERCIVAL HURDEN, OF HAREFIELD, ENGLAND

CONSTRUCTION OF CONCRETE BUILDINGS CAST IN SITU

Application filed January 20, 1927, Serial No. 162,231, and in Great Britain February 4, 1926.

This invention consists of an improvement in houses or buildings and the method of constructing the same wherein the walls are of concrete or similar material cast in situ between an inner lining or element of asbestos-cement or equivalent material, and an outer covering, facing or elements of asbestos-cement or equivalent material, the inner lining or elements being attached to a skeletal 5 ton structure of uprights or stanchions which are supported at their lower ends on the foundations of the house or similar building and are connected at their upper ends by transverse roof joists, and the outer covering 10 facing or elements being of trough shape and disposed lengthwise around the outside of the structure prior to the casting in situ of the wet concrete or similar material, the flanges of the trough shaped elements extending 15 towards the said uprights or stanchions and being bonded in position by the concrete or similar material when set. Where the walls are constructed in this manner, the outer covering, facing or elements is or are 20 adapted to be temporarily held in position by removable bars or to be held against displacement by transverse ties during the casting 25 of the wet concrete, the ties being attached to the uprights or stanchions or parts thereon and the said outer facing, covering 30 or elements.

The object of the present invention is to provide improvements in the method of constructing the house or similar building of the kind hereinbefore mentioned, the improvements having for effect to facilitate securing the outer facing, covering or elements in position or to the uprights or stanchions, and to provide an improved horizontal waterproof 35 joint between adjacent elements forming the outer facing or covering irrespective of pointing or similar material which may be used between the adjacent elements.

According to this invention the method is 40 improved by so constructing and arranging the trough, flanged or equivalently shaped elements that they are adapted to overlap each other throughout their entire length at their horizontal edges in order to close the 45 horizontal joints, and the overlapping parts

are bonded in the concrete or similar material cast in situ between the said elements and the inner lining. For effecting the overlapping of the elements they are provided with a marginal portion extending at an angle from 55 one of the longitudinal flanges and capable of being disposed between the edge of the flange of an adjacent element and the said uprights or stanchions and of engaging with the concrete or similar material in the trough 60 or channel portion of the said adjacent element. The said marginal portions extend at an angle to the adjoining flanges on one side of the troughs or channels, while the flanges on the opposite sides when the elements are 65 arranged in position, form the bottom of the troughs or channels into which the concrete or similar material is cast. In lieu of or in addition to holding the elements in position by removable bars or transverse ties, the 70 marginal portions may be connected to the uprights or stanchions by securing devices capable of engaging such portions and the parts of the uprights or stanchions in proximity thereto or with which they are 75 arranged in contact. Further, the bottom flanges may also be secured to the uprights or stanchions by clamping or securing devices capable of engagement with the bottom flanges and the uprights or stanchions. 80 Where securing devices are employed, the marginal portions and the bottom flanges may be formed with apertures, recesses or parts suitable for engagement therewith. Alternatively, the bottom flanges and the 85 marginal portions may be so constructed as to be capable of interlocking engagement with each other, for example, the bottom flanges may be formed with tongues or their equivalent and the marginal portions with openings for the reception thereof. The elements constituting the outer facing or covering are capable of being easily and quickly 90 secured in position relatively to the uprights or stanchions and the method of construction is facilitated and improved thereby.

In order that the said invention may be 95 clearly understood and readily carried into effect, the same will now be fully described 100

with reference to the accompanying drawings, in which:—

Figure 1 is a sectional elevation of part of a concrete or similar wall constructed according to this invention.

Figure 2 is a similar view to Figure 1 illustrating alternative constructions.

Figures 3 and 4 are perspective views of parts of two forms of the elements.

- 10 Referring to Figure 1, each of the elements of asbestos-cement or equivalent material comprises a body portion *a* which is curved outwards to a slight extent, side flanges *b* and *b*¹ and the marginal portion *c*, the latter extending from the side flange *b* and being adapted to be disposed beneath the edge of the side flange *b*¹ of an adjacent element, and to be embedded in the concrete or similar material *d* cast between the elements concerned and the inner lining *e* of asbestos-cement sheeting or equivalent material. The elements are of much greater length than width and are disposed horizontally around a framework constituted by uprights or stanchions *f* erected on the foundation of the building to be erected. In constructing the building, the inner lining *e* is secured to fillets *g* attached to the inside surfaces of the uprights or stanchions *f* forming the framework, and the elements are horizontally disposed around the latter with the side flanges extending towards the same. After thus arranging one course of elements around the framework and temporarily supporting them in position by removable bars in the known way, the space between the inner lining and the elements is filled in with wet concrete or similar material by casting the same therein. The concrete or similar material thus introduced extends into the elements and between the uprights or stanchions constituting the framework as well as between the latter and the body portions of the elements, and surrounds and embeds the parts of the marginal portions *c* projecting into the space between the adjacent element and the uprights or stanchions. In this manner the elements are effectively keyed in the concrete or similar material, and no portion of the latter is left uncovered by the elements which form the outer facing of the wall. The spaces between the flanges *b*, *b*¹ of adjacent elements is filled in with pointing material *h*. To interlock the uprights or stanchions *f* in the concrete or similar material they are formed with apertures *i* in the web portions.

uprights or stanchions *f* by the provision of openings in the flanges thereof. As shewn in Figure 2, the hooks *l* extend over the marginal portion *c* of the adjacent element and serve to hold the latter against the uprights or stanchions *f* through the medium of the flange *b*¹ the edge of which is held against the marginal portion *c* by the said hooks. In this method of construction, the hooks *l* are adapted to hold the lower flanges *b*¹ in position relatively to the uprights or stanchions *f* by engagement with the apertures *k* while the upper flanges *b* with the marginal portions *c* are held in position by the edges of the flanges *b*¹ engaging with the marginal portions *c*. In some cases it is advantageous to form apertures or openings in the marginal portions *c* as well as the lower flange *b*¹, as shewn in Figure 4, and to pass the clamping hooks *l* through the apertures or openings in both parts. The method of securing the element shewn in the lower part of Figure 2 consists in providing apertures *m* in the marginal portions *c* and openings in the flanges of the uprights or stanchions *f* and fitting bolts and nuts *n* therein.

A further alternative construction comprises the employment of elements with marginal portions *c* provided with slots or openings *o* and lower flanges *b*¹ with projections *p*, as shewn in Figure 3. In assembling the elements of this form the projections *p* on the lower flanges *b*¹ are engaged with the slots or openings. If desired the slots or openings *o* may have bolts engaged therewith, and the flanges of the uprights or stanchions.

What we claim and desire to secure by Letters Patent of the United States is:—

1. A building of concrete material, comprising a foundation, a skeleton structure of uprights disposed on the foundation, transverse roof members connecting the upper ends of the uprights, a lining of asbestos-cement secured to the inside faces of the upright members of the skeleton structure, trough shaped elements of asbestos-cement provided with sides and marginal portions, and arranged round the skeleton structure with the sides of the elements disposed horizontally and the marginal portions arranged between adjacent troughs and the uprights, and concrete material in the spaces between the inner lining and the outer elements and embedding the said marginal portions as well as the uprights.

2. A building of concrete material, comprising a foundation, a skeleton structure of uprights disposed on the foundation, transverse roof members connecting the upper ends of the uprights, a lining of sheet asbestos-cement secured to the inside faces of the skeleton structure, horizontal open ended trough shaped elements of asbestos-cement arranged round the skeleton structure and

each provided with an upper flange and a lower flange and a marginal portion on the upper flange the marginal portion being arranged between the upper adjacent element and the uprights, securing devices engaged
5 with the marginal portions and the uprights, attachment devices between the marginal portions and the contiguous lower flange of the adjacent trough shaped elements, and concrete material which is disposed in the spaces
10 between the inner lining and the outer elements around the said marginal portions as well as the uprights.
